SHOE SHINE BOX

Harry H. Gerstner, Dayton, Ohio

Application April 7, 1932. Serial No. 603,721

3 Claims. (Cl. 15—265.)

This invention relates to new and useful improvements in shoe-shine boxes.

It is one of the principal objects of my invention to provide a shoe-shine box having a shoe holder that is raised out of, and above, the box to a firm shoe-supporting position by the hinged cover or top when the latter is brought to its fully open position. When this occurs the holder will solidly support a shoe in a convenient position for shining.

It is another object of my invention to secure to the interior portion of the box cover, a pivoted shelf to support cans of shoe polish in a raised position immediately in front of the shoe to be shined.

A further object of my invention is the provision of a shoe box in which articles may be stored beneath the shoe holder, which rests just below the box cover when the latter is in its closing position.

Another object of my invention is the provision of a shoe-shine box that may be used as a stool in its closed position, being attractively constructed with a seat top.

Other important and incidental objects will be brought out in the following specification and particularly set forth in the subjoined claims.

In the accompanying drawing illustrating my invention, Figure 1 is a perspective view of my shoe-shine box open, with the shoe holder and the shoe polish support in their raised positions. Figure 2 is a longitudinal, sectional view taken through the same, disclosing the link connection between the cover and the shoe holder. And Figure 3 is a side view of the box in its closed position for use as a stool, the retracted foot holder, shoe polish support and connecting link-age being shown in dotted lines.

In the accompanying drawing illustrating my invention, the numeral 1 designates a rectangular shoe-box having a bottom 2 and four legs 3. Secured by means of hinges 4 to the rear side 5 of the box is a four-sided cover 6. Pivots secured, near its rear corners, between the sides 7, 7 of this cover, is a shoe polish supporting shelf 8.

The numeral 9 designates a shoe holder, being constructed of metal to conform to the bottom of the shoe to be polished. Formed on the under-surface of this holder 9 at the juncture of its heel and instep supporting portions, are two parallel ears or lugs 10 between which one end of an arm 11 is pivotally secured. The other end of this arm is pivotally connected to a bracket 12 attached to the upper inner portion of the front

side 13 of the box. In its vertical position this arm forms a solid support for the heel portion of the shoe holder 9.

Formed on the front inner portion of the shoe holder 9 are two ears or lugs 14 between which the contiguous parallel ends 15, 15 of two inclined lever arms 16, 16, respectively, are pivoted. Each one of these inclined lever arms 16 terminates at its inner end in a vertical portion 17.

Set in horizontal grooves 18, 18 in the sides 19, 19, respectively, of the box 1, near the top edges thereof, are two oppositely disposed metal pieces or strips 20, 20, each strip being secured within its respective groove by screws 21. To the front portions of the metal strips 20, 20, the vertical portions 17 of the inclined lever arms 16, 16 are pivotally secured by fulcrum screws 22, the ends of said arms below the screws being pivotally connected to the curved outer ends of links 23. At their rear ends, these links 23, 23 incline upwardly for pivotal connection to shelf-supporting arms 24, 24 respectively, which are secured at their extreme lower ends, by pivot pins 25, to the rear portions of the metal strips 20.

At their upper ends the arms 24, 24 are secured by pivot pins 25 to the ends of the shelf 8 near the front sides thereof, this shelf being formed with round recesses 26 to receive cans or containers holding polish for use in shining the shoe in place upon the holder 9.

Stop pieces 27, 27, with inclined front edges, are secured to the upper inner corner portions of the sides 19, 19, respectively, of the box, to limit the rearward movement of the shelf supporting arms 24.

When the box is not in use for the purpose of shining one's shoes, it is in the closed condition illustrated in Figure 3. So that it may be used as a stool while in this condition, a leather cushion 28 is fitted to the top portion of the cover 6.

When the cover 6 is raised to the position shown in Figure 1, the shoe holder 9 will be elevated to the position illustrated in that figure by the mechanism just described. This mechanism, which is retracted within the box while the latter is closed, as shown in dotted lines in Figure 3, will be actuated as follows by the rearwardly moving cover to bring the holder 9 to its shoe-supporting position.

When the outer ends of the shelf-supporting arms 24 are drawn upwardly and rearwardly by the shelf 8 pivotally secured to the cover 6, they will pull rearwardly the links 23 which are connected to them. The front ends of these

80

85

90

95

105

110

links, being secured to the extreme lower ends of the lever arms 16, will exert a rearward pull upon these ends to cause the inclined ends of these arms to move the shoe holder 9 upwardly and 5 forwardly, until the arm 11, which follows the movement of the inclined portions of the lever arms 16, to abut the top edge of the front side 13 of the box.

At this point the shelf supporting arms 24, 24 10 engage the stop pieces 27, 27 respectively, which assist the front side 13 of the box in affording a solid support for the shoe holder in its raised position.

When the shoe holder is in its top position, as 15 shown in Figures 1 and 2, it is high enough and solid enough to permit one to conveniently and efficiently shine his or her shoes when separately placed upon it. At the same time the shelf 8 will be firmly held by the arms 24 in a 20 sufficiently raised horizontal position to afford to the user convenient access to the polish supported upon it.

When the cover 6 is moved downwardly to close the box, the shelf 8 carrying the polish will 25 be maintained in a horizontal position, coming to a stop in that position over the shoe holder 9, which will be drawn downwardly and rearwardly below it by the links 23. (See Figure 3.)

It will be seen that after the shoe holder and 30 the polish holding shelf have been retracted within the box, ample room is available below them and their elevating mechanism to receive various household articles for storage.

Having described my invention, I claim:

35 1. The combination with a shoe box, a cover hinged thereto, a foot rest within the box, a shelf pivotally secured to the inner portion of the cover, and linkage connected between said shelf and foot rest, whereby, when the free end of the cover 40 is drawn upwardly and rearwardly, the foot rest

will be elevated out of the box to a foot-supporting position above the latter, opposite the shelf, and the shelf will remain approximately horizontal.

2. The combination with a shoe box, a cover 80 hinged thereto, a foot rest movably supported within the box, a polish-supporting shelf pivotally secured, near its rear edge, to the inner portion of the cover, a lever arm pivotally secured at its lower end within the box near the hinge and to the outer portion of said shelf, the distance between the hinge and the lower lever pivot being approximately equal to the distance 85 between the pivot of the shelf to the cover and the pivot of the lever to the shelf, and linkage between the foot rest and the lever arm, whereby, when the free end of the cover is drawn upwardly and rearwardly, the foot rest will be elevated out of the box to a foot-supporting position 90 above the latter, opposite the shelf, and the shelf will remain approximately horizontal.

3. The combination with a shoe box, a cover 95 hinged thereto, an arm pivotally secured at its lower end to the inner portion of the front side 100 of the box and projecting above the latter when in its raised position, a foot rest pivotally secured to the upper portion of said arm, a lever also pivotally secured at its upper end to said foot rest, a fulcrum pin pivotally securing said lever near the front of the box, the lower end of 105 said lever being free, and link connected between the cover and the free lower end of said lever, the lever being so shaped that its fulcrum is above the line joining the two ends of the link 110 to raise its outer end, and through the foot rest 115 the outer end of the said supporting arm, out of the box until said arm engages the top edge of the front side of the box, to solidly support the foot rest in a shoe-shining position.
